WATERPROOF RECEPTACLE

Filed July 20, 1928

UNITED STATES PATENT OFFICE

ARTHUR VON FRANKENBERG, OF NEW YORK, N. Y.

WATERPROOF RECEPTACLE

Application filed July 20, 1928. Serial No. 294,094.

This invention relates to waterproof receptacles, such as cigarette cases and the like, adapted to be used as a bathing suit accessory, and for like purposes.

5 An object of the invention is to provide a receptacle of the character described, which shall be positively waterproof and yet have means for readily opening and closing the same, and shall be of practical and economical construction.

10 An object of this invention is to provide a waterproof receptacle of the character described having a hingeless cover and improved means for readily opening and closing said cover.

15 A further object of this invention is to provide a structure comprising few and simple parts, which shall be relatively cheap to manufacture, and practical and efficient to 20 a high degree in use.

Other objects of this invention will in part be obvious and in part hereinafter pointed out.

The invention accordingly consists in the 25 features of construction, combinations of elements, and arrangement of parts which will be exemplified in the construction hereinafter described, and of which the scope of application will be indicated in the following claims.

30 In the accompanying drawing, in which is shown one of the various possible illustrative embodiments of this invention,

Fig. 1 is a sectional elevational view of the 35 receptacle embodying the invention showing the cover actuating mechanism at one side of the receptacle.

Fig. 2 is a partial cross-sectional view taken on line 2—2 of Fig. 1.

40 Fig. 3 is an enlarged plan view of the actuating mechanism at one side of the receptacle.

Fig. 4 is a cross-sectional view taken on line 4—4 of Fig. 2, but showing the cover 45 slightly opened.

Fig. 5 is a view similar to Fig. 4 but showing the cover entirely opened.

Fig. 6 is a top plan view of the receptacle with the cover open.

50 Referring in detail to the drawing, 10 de-

notes a waterproof receptacle embodying the invention adapted to be used as a bathing suit accessory in the form of a cigarette case. Said receptacle is seen to comprise a container 11 having a bottom wall 12, a 55 front wall 13, a rear wall 14 and end walls 15, 15^a. The front wall 13 is preferably made of greater height than the rear wall 14, the top portion 16 of end walls 15, 15^a, being formed at an angle to said front and 60 rear walls. Said front, rear and side walls of the container 11 are bent inwardly at the upper portions thereof and terminate in a short upstanding portion 17 encircling said container and forming a contracted portion 18 for seating a complementary cover 19 for 65 said receptacle.

Said cover 19 is formed with a top wall 20, a rear wall 21, and triangular end walls 22, 22^a. The lower edge portions 23 of said 70 end walls 22, 22^a, are formed at an angle corresponding to the angle of the upper portions 16 of end walls 15, 15^a; and the top wall 20 of the cover is parallel to the bottom wall 12 of the receptacle when said cover 75 is seated on said receptacle. The open end portions of the cover 19 are formed with a bead 24 encircling said cover and adapted to fit the seat 18 of the receptacle. Packing means such as a strip or layer of rubber 80 may be stuffed into said bead for contacting the upstanding portion 16 of said seat 18 to insure a water-tight seal for the receptacle.

The receptacle 11 is provided with partitions 30 adjacent the end walls 15, 15^a, and 85 spaced therefrom to form a chamber 31 at each end of the receptacle. Said partitions 30 may be formed with inwardly bent flanges 32 contacting the bottom wall 12 and front and rear walls 13, 14. Said partitions 90 may be secured to said walls by soldering the flanges 32 thereto, or in any other suitable manner. The upper ends of said partition may be formed with outwardly bent extensions 33 engaging the upstanding portions 17. Said extensions form closures for the chambers 31, except for a slot 34 provided in each of said extensions for a purpose hereinafter appearing.

95 The space between the partitions 30 forms 100

a chamber 35 for receiving a package of cigarettes 36. The receptacle 10 is adapted to be attached to a bathing-suit belt 37 as by the threading through the spaced vertical posts 38 of buckle 39, which may be secured to the receptacle by soldering to the front wall 13 thereof, or in any other suitable manner.

Means is provided for closing and opening the cover 19. Said means comprises similar mechanism at each end of the receptacle, housed within chambers 31. The cover actuating mechanism at one end only of said device will therefore be described. Said mechanism comprises a Z-shaped arm 40 having a portion 41 secured to the wall 22 of cover 19, at the inner surface thereof, and a portion 42 extending downwardly through slot 34 and into chamber 31. Said portion 42 is formed with an angular extension 43 pivoted at its free end 44 to the mid-portion of a floating lever 45, provided at the end thereof adjacent the front wall 13 with a lug 46. A tension spring 47 is preferably connected at one end thereof to said lug 46, and at its other end to a pin 48 integral with partition 30. The end of said lever 45 adjacent the rear wall 14 is enlarged into a bean shaped portion 49 curved to fit into the corner formed by said rear wall 14 and closure member 33. Said lever 45 is preferably made of a metal stamping and portion 49 thereof is preferably shaped to provide a longitudinal guiding groove 50 adapted to receive a projection 51 formed at one end of a lever 52 pivoted immediately the ends thereof to a supporting lug 53 extending from partition 30. Said lever 52 is pivoted for movement in a plane transverse to the plane of movement of lever 45. The lower end portion 54 of said lever 52 is pressed outwardly by a small compression spring 55 to maintain the projection 51 within the groove 50. The portion of the lever 45 below the groove 50 is shaped to form a ramp 56, the function of which will appear hereinafter in the description of the operation of the device.

A fixed pin 57 extends from and at right angles to partition 30 into the chamber 31. Said pin is so located as to be slightly below the floating lever 45, and between lug 46 and pivot point 44 of said lever when the cover 19 is clamped on the container 11 (see Fig. 1).

Each of the end walls 15, 15^a, of said receptacle 11 may be formed with an outwardly recessed portion 60 at a point substantially adjacent the lower end portion 54 of lever 52. Said recessed portion 60 provides more or less resilient areas on each side of the box 11 which may be pressed inwardly by the fingers, and upon release of finger pressure return to normal position.

6 A short pin 61 is mounted on one end of arm

52 in alignment with compression spring 55. The length of said pin 61 is such that when projection 51 of lever 52 is received in groove 50, portion 54 of said lever contacts with said pin. Compression spring 55 retains said portion 51 in contact with pin 61 and said projection 51 in engagement with lever 45.

As above stated, the cover actuating mechanism described is the same at both ends of the receptacle 11, and forces acting on the cover are thus balanced. Fig. 1 shows the cigarette case with the cover 19 tightly clamped.

In this position, each spring 47 within the compartments 31 pulls down at one end of floating lever 45, while the other end 49 of said lever is anchored by the lever 52 which is fixed to pin 53. The springs 47 tending to pivot the lever 45 about projection 51 as a fulcrum, exert downward forces on the arms 40 which in turn pull down on the cover 19. In this position the cover is seated on the seat 18 and the gasket 25 provides a watertight seal between the cover 19 and container 11.

To open the cover to permit removal of cigarettes, two simple operations are required. First, the recessed portions 60 at each end of the box are pressed inwardly by the fingers of the user, the push-button 61 consequently pressing the lower ends 54 of levers 52 and moving them against the pressure of said spring 55. The levers 52 are thus pivoted about pin 53, the projections 51 swinging out of grooves 50 and thus disengaging from the floating levers 45. This movement permits springs 47 to pull down on projections 46 to rock the levers 45 about fixed pins 57 which abut said levers as soon as downward movement thereof begins. This rocking movement exerts an upward force on the arms 40 which slightly lifts the cover 19 to the position shown in Fig. 4. Further lifting movement is prevented when the curved portion 49 strikes the corners formed by the rear wall 14 and oblique closure 33.

The cover 19 may now be further opened from the position shown in Fig. 4 to that of Fig. 5 by pressing the front edge of the cover backward against the tension of springs 47. During this movement, the floating levers 45 pivot about their curved ends 49 and the pins 51 of levers 52 ride up the ramps 56 and into the grooves 50. Cigarettes may now be removed from or inserted into the receptacle 11 while the cover is held in this open position. It will be noted that during the last mentioned opening movement, the lower edge of rear wall 21 of the cover contacts the rear wall 14 and slides down a short distance from the upper edge thereof.

To allow the cover 19 to shut it is merely

necessary to remove the fingers holding said cover in open position. Upon release of finger pressure, the springs 47 exert a strong downward pull on the projections 46 of the floating levers 45. Said levers are thereby pivoted on projections 51 which are now the fulcrum points for said levers. Said pivotal movement of the floating levers 45 pull the arms 40 down and swing the cover into seating position which is facilitated by the contracted position 17 of the seat 18.

It will thus be seen that there is provided a device in which the several objects of this invention are achieved, and which is well adapted to meet the conditions of practical use.

As various possible embodiments might be made of the above invention, and as various changes might be made in the embodiment above set forth, it is to be understood that all matter herein set forth or shown in the accompanying drawing is to be interpreted as illustrative and not in a limiting sense.

Having thus described my invention, I claim as new and desire to secure by Letters Patent:—

1. In a water tight receptacle of the character described, in combination with a container and a cover therefor, hingeless means for actuating said cover to open or closed position.

2. In a water tight receptacle of the character described, in combination with a container and cover therefor, means for actuating said cover to open or closed position, said means comprising a floating lever connected immediately the ends thereof to said cover, and tension means secured to said lever.

3. In a water tight receptacle of the character described, in combination with a container and cover therefor, means for actuating said cover to open or closed position, said means comprising a floating lever connected immediately the ends thereof to said cover, tension means secured to said one end of said lever and means for removably engaging the opposite end portions of said lever.

4. In a water tight receptacle of the character described, the combination with a container and a cover therefor, of a single tensioning means for opening and closing said cover.

5. In a water tight receptacle of the character described, in combination with a container and a cover therefor, means for actuating said cover, said means including a floating lever pivotally secured to said cover member.

6. In a water tight receptacle of the character described, in combination with a container and a cover therefor, means for actuating said cover, said means including a floating lever pivotally secured to said cover

member, and tension means connected to said lever and receptacle.

7. In a water tight receptacle of the character described, in combination with a container and a cover therefor, means for opening said cover, said means comprising a floating lever connected to said cover, and a means fixed to said container acting as a fulcrum for said lever during said opening movement.

8. In a water tight receptacle of the character described, in combination with a container and a cover therefor, means for opening said cover, said means comprising a floating lever connected to said cover, tension means secured to said lever at one end thereof, and means fixed to said container forming the fulcrum for said lever during said opening movement.

9. In a water-proof receptacle of the character described in combination with a container and a cover therefor, means for actuating said cover to open and closed position, said means comprising a plurality of levers movable in transverse planes.

10. In a water-proof receptacle of the character described, in combination with a container and a cover therefor, means for opening said cover, said means including a floating lever connected to said cover, a second lever pivoted to said container, engaging said floating lever, means for retaining said levers in engagement, and means for moving said second mentioned lever in a plane transverse to said floating lever to disengage said levers.

11. In a water-proof receptacle of the character described, in combination with a container and a cover therefor, means for opening said cover, said means including a floating lever connected to said cover, a second lever pivoted to said container engaging said floating lever, means for retaining said levers in engagement, means for moving said second mentioned lever in a plane transverse to said floating lever to disengage said levers, and tension means for moving said floating lever upon disengagement to lift said cover.

12. In a water-proof receptacle of the character described, in combination with a container, and a cover therefor, means for opening said cover, said means including a floating lever connected to said cover, a second lever pivoted to said container, and means engaging said floating lever, means for retaining said levers in engagement, and means for moving said second mentioned lever in a plane transverse to said floating lever to disengage said levers, tension means for moving said floating lever upon disengagement to lift said cover, and means integral with said container forming a fulcrum for said floating lever at one end there-

of during further opening movement of said cover.

13. In a water tight receptacle of the character described, in combination with a container and a cover therefor, hingeless means for actuating said cover to open or closed position, said means including means for locking the cover to said container in closed position.

10 In testimony whereof I affix my signature.
ARTHUR VON FRANKENBERG.
